UNITED STATES PATENT OFFICE.

SIGMUND HELLER, OF CHICAGO, ILLINOIS.

PHOTOGRAPH-HOLDER.

1,040,320.

Specification of Letters Patent.

Patented Oct. 8, 1912.

Application filed March 20, 1912. Serial No. 685,111.

To all whom it may concern:

Be it known that I, SIGMUND HELLER, a citizen of the United States, residing at Chicago, in the county of Cook and State of Illinois, have invented a certain new and useful Photograph-Holder, of which the following is a description, reference being had to the drawings forming a part of this specification.

10 My invention has for its object the provision of a pocket or holder for the reception and display of a photograph or like picture in a setting of textile fabric, which will present a neat and finished appearance and 15 retain its shape and serve its purpose efficiently, and which is particularly adapted for the embellishment and ornamentation of flags, banners, pennants, etc., and also for use on pillows, draperies and various other 20 hangings of cloth.

In the drawings Figure 1 is a front view of my novel holder; Fig. 2, a back view; Figs. 3 and 4 front views of modified forms of the holders, portions of the different layers of cloth being broken away in the several figures mentioned to exhibit the relation of the different parts, and lines of stitching being indicated by dotted lines, and the outline of hidden parts being indicated by broken lines; Fig. 5 is a detail section through the snap button by which the ground A and rear piece C are detachably secured together to close the pocket between the two; and Fig. 6 is a view of a pennant 35 to which my invention is applied.

The same letters of reference apply to all the figures.

The cloth A of the article upon which the holder is formed is cut away to the exact 40 size of the display opening of the holder, and a facing panel of reinforcing cloth B having an opening of the same size is applied to the front thereof, so that the openings will lie in registration, a line of stitching a around the margin of the opening serving to secure the two plies smoothly and firmly together and prevent any unsightly bagging or stretching of the cloth around the margin of the field of view of the photograph. To the rear side of the ground 45 or body cloth A is applied a piece of cloth C of proper size, which is secured to the cloth A at the bottom and both sides by a line of stitching b, the top being left open so that a pocket is thereby formed for the 50 reception of a photograph. This line of stitching may be the same line b by which the reinforcing panel B is secured to the cloth A, but in such case the stitching of course extends only through the parts A and B along the top line. However, either the part B or the part C may be the larger, in which case a second line of stitching c will be used to secure the rear piece C to the ground; as illustrated in Fig. 3, in which 55 the facing panel B is the larger and the stitching c lies inside the stitching b; and Fig. 4, in which the part C is the larger and the line of stitching lies outside the stitching b.

A snap button D may be advantageously used at the top of the piece C to secure it to the ground or body cloth A, though this is not indispensable to a practical embodiment of my invention. As shown in Fig. 5, 70 the button is preferably of the kind in which the parts are secured to the plies of fabric by stitching, in order that they may be entirely concealed from notice. If desired a sheet of transparent celluloid film may be 75 used in the holder to cover and protect the face of the photograph.

I claim:

1. A holder for displaying a photograph or like picture comprising a ground or body of textile fabric cut away to form a display opening, a front display facing or panel having a registering opening and secured to said ground by a line of stitching around its outer edge and a line of stitching around 85 said display opening, and a rear piece or portion forming a pocket secured to said ground by a marginal line of stitching along its bottom and sides.

2. A holder for displaying a photograph or like picture comprising a ground or body of textile fabric cut away to form a display opening, a front display facing or panel having a registering opening and secured to 90 said ground around said opening by a line 95 100 of stitching, and a rear piece or portion forming a pocket for the reception of the picture, said front panel and rear piece being secured along their margins to said 5 ground by a line of stitching extending through all three of them along the bottom and both sides of said panel and extending only through said ground and panel along the top of the latter.

SIGMUND HELLER.
